LAMINATED PHOTOGRAPHIC MATERIAL
AND PROCESS FOR PRODUCING THE
SAME

Miller Reese Hutchison, New York, N. Y., assignor, by mesne assignments, to Ralph G. Luff, Philadelphia, Pa.

Original application July 12, 1941, Serial No. 402,128, now Patent No. 2,311,547, dated February 16, 1943. Divided and this application October 24, 1941, Serial No. 416,334.

14 Claims.

(Cl. 95—8)

1

This invention relates to a process for immunizing hygroscopic sheet materials against dimensional variations and to the product thereof. The application is a division of my copending application Serial No. 402,128, filed July 12, 1941, which has since matured into Patent No. 2,311,547, dated February 16, 1943.

In the parent application, commercial processes are described, calling for the use of hygroscopic sheet material which is immune to dimensional variations resulting from changes in atmospheric moisture. In general, the sheet material referred to presents a surface processed for the application of pictorial representations, line work, or the like as for instance, drawing paper or tracing cloth on which a design can be drawn, or paper presenting a surface coated with a light sensitive emulsion upon which a design photographically can be printed. Ordinary drawing paper, tracing cloth, photographic paper, etc., are hygroscopic, i. e., they absorb atmospheric moisture. Thus, on damp days, such materials expand, whereas on dry days, they contract. Therefore, two points or lines, located several feet apart, on such materials, will be located further apart on a wet day, than on a dry day. Consequently, such materials cannot be used where it is desired to make drawings, or copies of drawings, from which dimensions can be scaled, or where it is desired to maintain accuracy in the dimensions of the drawings or copies, over long periods.

According to the present invention, it is proposed to immunize such sheet materials against dimensional variations, resulting from changes in atmospheric moisture, by adhering them to backing elements which, themselves, are immune to such changes, as for instance, metal or glass, depending, of course, on the service for which the sheet materials are intended. A water-proof thermo-plastic is used to effect a bond between the sheet material and the backing element and again, depending upon the service, variations in the technique of effecting the bond, are employed, all of which fully are set forth in the following detailed description in conjunction with the accompanying drawings wherein.

Fig. 1 is a sectional view, greatly enlarged, depicting a portion of a sheet of drawing paper, backed with sheet metal;

Fig. 2 is a sectional view, greatly enlarged, depicting a portion of a sheet of paper having a thermo-plastic coating, prior to being backed with metal;

Fig. 3 is a sectional view, greatly enlarged, of

2

a portion of a metal sheet which has been given a thermo-plastic coating, prior to being faced with paper;

Fig. 4 is a diagrammatic view illustrating the manner in which the thermo-plastic coated paper and metal sheet, of Figs. 2 and 3 are adhered;

Fig. 5 is a sectional view, greatly enlarged, and depicting a portion of a sheet of photographic paper thermo-plastically adhered to a sheet of metal;

Fig. 6 is a sectional view, greatly enlarged, and depicting a portion of a sheet of photographic paper thermo-plastically adhered to a sheet of glass; and

Fig. 7 is a sectional view, greatly enlarged, depicting a portion of a sheet of paper coated, on one side, with a photographic emulsion and, on the opposite side, with a thermo-plastic.

In Fig. 1, there is depicted a sheet of drawing

paper A adhered to a sheet of metal B (template stock in the neighborhood of $\frac{1}{16}$ " in thickness) by an intermediate thin layer of thermo-plastic C. The drawing paper A must have certain characteristics, to render it suitable for the function

it has to perform. Thus, since the maintenance of accurate dimensions upon the sheet is of prime importance, the plasticized paper should be very thin, preferably not more than three-thousandths

of an inch thick, in order that given areas on the outer surface of the sheet will not vary from the corresponding areas on the inner surface thereof which is adjacent the backing element. The paper, also, should be very smooth, otherwise the pencil point quickly will be dulled, making the lines of varying width; this despite the fact that a special black pencil, of extreme hardness, is recommended for accurate work. It is essential that all of the pencil-drawn lines be thin and sharply defined, since dimensions, accurate to a thousandth of an inch, may be involved.

Toughness of paper also is a requisite, because erasures must be made and also because, in some cases, it may be desired to machine the metal backing element, in accordance with the drawing

on the paper with which it is surfaced. Such machining operations might involve the use of saws, files, sanders and millers which have a tendency to pull the paper apart and which might, in the absence of proper paper strength, result

in destroying the integrity of the lines, at the point of machining.

The thermo-plastic must also have special characteristics. It must be insoluble in water, so as to be unaffected by atmospheric dampness

and its melting point must be greater than are

the temperatures generated by sawing, filing, sanding or milling the metal backing element, when that is done, or the paper would separate, at the point of machining, from the metal and thus destroy the integrity of the design. A thermo-plastic having a softening point of about 300° F. is recommended for this purpose. Thermo-plastics, having such characteristics, currently are on the market.

Care must be exercised, in the process of adhering the paper to the backing element, to insure a surface free of surface inequalities and to insure, also, that there be an entire absence of air or gas pockets between the paper and the metal: otherwise, the integrity of the drawing would be destroyed, since the dimensions of the paper on and in the vicinity of the air or gas pockets, would vary with changes in atmospheric moisture, for the reasons previously pointed out. To obtain a good product, it is preferred to coat one surface of the metal with thermo-plastic, as well as that surface of the paper which, in the completed stock, will be adjacent the metal, since two thermo-plastic surfaces more intimately will form a firm bond, than can possibly be secured if only one of the two surfaces is coated. A coating of thermo-plastic may be applied to the paper by looping the latter transversely and drawing it over the surface of liquid thermo-plastic, as is done when coating paper with photographic emulsion. If the paper then is drawn over a roller, past a scraper located at a fixed distance from the coated surface of the paper, the surplus plastic will be scraped off leaving a coating of definite thickness upon the paper. Figs. 2 and 3 illustrate, respectively, a sheet of paper A and a sheet of metal B, both coated with thermo-plastic C and before being joined together.

The manner in which the paper and the metal backing element, both previously covered with thermo-plastic, are adhered together, is illustrated in Fig. 4. The necessary apparatus consists of a frame, somewhat similar to a vacuum printing frame, in that it includes a base member D and a top flexible member E capable of being brought together to define a compartment F, from which air can be exhausted. The base D is capable of being heated, preferably by electricity, in order that the temperature may accurately be controlled. The backing element B is laid, coated surface up, on the preheated base plate D and the paper, coated surface down, on top of the backing element. In other words, the plastic layers, on the paper and on the backing element, are placed in contact, after the base plate D has been heated.

When the backing element and paper are in position, the frame is closed. Heat, having previously been applied to bring the hot plate temperature up to the melting point of the thermo-plastic (i. e., about 300° F.), the air is exhausted from the chamber F, until a vacuum of about thirty inches of mercury is obtained. These conditions are held, for a definite period of time, usually five minutes, during which period not only is all the air and whatever gas may be given off by the melted thermo-plastic, extracted from what otherwise would be the space between the metal and the paper, but the paper is firmly pressed, throughout its entire area, to the surface of the metal, by the action of the vacuum-actuated flexible member E. When the thermo-plastic thus has been cured, the bond is complete and the drawing paper, thoroughly immunized

against dimensional variations, is ready for use.

In Fig. 5 there is shown a sheet of paper G, surface-coated with an unexposed photographic emulsion H and adhered to a metal backing element I by an intermediate layer of plastic J. As regards thinness and toughness, the photographic paper must have the same characteristics as the drawing paper previously described and for similar reasons. The thermo-plastic, in addition to possessing all of the qualities of that used for adhering the drawing paper to the metal backing must, in addition, be acid and alkali-proof, in order that the bond will survive the developing process.

The procedure followed, in applying the photographic paper to the metal backing, is the same as that used in applying the drawing paper to the metal backing.

A sheet of paper T coated, on one side, with a thermo-plastic U, and on the opposite side, with a light sensitive emulsion V, in itself, is believed to be new and is one of the features of the instant invention (Fig. 7). Special care must be exercised in preparing the paper before it is adhered to a backing element which is immune to dimensional variations. Thus, the thermo-plastic U should be applied before the emulsion V. This sequence is desirable since light sensitive emulsion easily is contaminated and also, since the thermo-plastic tends to stiffen the paper which is very thin—around three thousandths of an inch—thus making it easier to apply the emulsion when the paper loop is moved into and out of contact with the surface of the emulsion in the applying trough. Also, since photographic emulsions are sensitive to infra-red rays, as well as to visible light, an emulsion is used, the sensitivity of which initially is much higher than is required for printing; one being selected of such character that, after it has been subjected to the heat for the definite period of time required to cure the thermo-plastic, during the application of the sensitized paper to the metal backing, nevertheless will have a final sensitivity, correct for printing. Since the heat retained in the metal backing, after the cure of the thermo-plastic has been completed, would continue to effect the sensitivity of the emulsion, it is necessary that the product be cooled as expeditiously as possible and, for this purpose, suitable refrigerating means may be employed.

To be more specific, in adhering the photographic paper to its base, the heating unit previously must be brought to a definite temperature, which is held for a definite period to effect a proper cure of the thermo-plastic. With that as a consideration, a light sensitive emulsion is selected having an initial sensitivity gaged to permit a reduction to the proper value for printing at the conclusion of the plasticizing process. At the conclusion of the cure, the plasticized unit immediately is removed from the heating frame and placed in a refrigerating chamber. In other words, it is essential that the reduction in sensitivity accurately be controlled; otherwise, in the subsequent printing, there would be no way of accurately determining the light intensity and exposure time required for proper exposure in printing.

In Fig. 6, there is illustrated a sheet of photographic paper, immunized against dimensional variations by being adhered to a backing element of glass, rather than of metal as in the embodiment previously described. Such a product is used where the light, for effecting the exposure

of photographic emulsion, is required to pass through the backing element. The unit includes a sheet of plate glass K and a sheet of photographic paper L, adhered to the glass by means of a thin layer of thermo-plastic M. After the glass surface is coated with a thin layer of thermo-plastic, the paper is applied to the glass, in the same manner as is the photographic paper applied to the metal backing element and which previously has been described. Here, too, the paper must be attached to the surface of the glass, over its entire area, since it must be immune to dimensional changes. The thermo-plastic, in addition to being water, acid and alkali-proof, must also be transparent, to permit the passage of light. There is also followed the same procedure of using an emulsion of originally higher sensitivity than is required for printing, since here, too, the sensitivity of the emulsion suffers as a result of the heat applied during the curing of the thermo-plastic, to attach the paper to the glass. In other words, the initial sensitivity of the emulsion is such that, after it has been in the heating frame for the length of time required to cure the thermo-plastic, say about five minutes, the sensitivity will have dropped to the desired point for printing.

In the accompanying drawings, the invention has been illustrated merely in preferred form and by way of example, but obviously many variations and modifications may be made therein which will still be comprised within its spirit. It is to be understood, therefore, that the invention is not limited to any specific form or embodiment, except insofar as such limitations are specified in the appended claims.

Having thus described my invention, what I claim is:

1. In the preparation of material having a photo-sensitive surface and which is immune to plane dimensional variations resulting from changes in atmospheric moisture, the process which includes coating one side of a sheet material with a photographic emulsion having a sensitivity greater than is that necessary for the service intended, adhering the sheet material to a backing element immune to plane dimensional variations resulting from changes in atmospheric moisture by means of a layer of water-proof heat-setting adhesive located between the reverse side of the sheet material and the backing element and which is heated to the setting point to effect a bond between the sheet material and the backing element, the initial sensitivity of the emulsion being sufficient to compensate for a reduction in sensitivity which is occasioned by the heat applied.

2. The process according to claim 1, wherein the sheet material is pressed firmly against the backing element during the heating step.

3. The process according to claim 1, wherein the heating step is carried out in a substantial vacuum.

4. The process according to claim 1, wherein the total heat allowed to affect the photographic emulsion is controlled so as to avoid reducing its sensitivity beyond that suitable for the use intended.

5. The process according to claim 1, wherein the unit is subjected to rapid cooling after the adhesive has been set in order to arrest the action of the heat upon the emulsion, thereby to insure that the reduction in sensitivity occasioned by the heat will not render the photo-sensitive surface unsuitable for the use intended.

6. As an article of manufacture, a laminated unit comprising a backing element immune to plane dimensional variations from changes in atmospheric moisture, and a sheet material adhered thereto by means of a water-proof heat-set adhesive and surface-coated with an unexposed light-sensitive photographic emulsion, the heat-setting of the adhesive in bonding the sheet material to the backing element having the effect of materially reducing the sensitivity of the photographic emulsion, and the initial sensitivity of the emulsion being sufficiently greater than that necessary for the service intended to compensate for said reduction in sensitivity.

15 7. As an article of manufacture, a laminated unit comprising a metal backing element and a sheet material adhered thereto by means of a water-proof heat-set adhesive and surface-coated with an unexposed light-sensitive photographic emulsion, the heat-setting of the adhesive in bonding the sheet material to the backing element having the effect of materially reducing the sensitivity of the photographic emulsion, and the initial sensitivity of the emulsion being sufficiently greater than that necessary for the service intended to compensate for said reduction in sensitivity.

20 8. As an article of manufacture, a laminated unit comprising a glass backing element and a sheet material adhered thereto by means of a water-proof light-transmitting heat-set adhesive and surface-coated with an unexposed light-sensitive photographic emulsion, the heat-setting of the adhesive in bonding the sheet material to the backing element having the effect of materially reducing the sensitivity of the photographic emulsion, and the initial sensitivity of the emulsion being sufficiently greater than that necessary for the service intended to compensate for said reduction in sensitivity.

25 9. As an article of manufacture, adapted to be adhered by the application of heat to a backing element for use in a photographic process for producing on a surface of the material to be fabricated an accurate replica of some particular image, a flexible sheet material coated on one side with a water-proof heat-setting adhesive and coated on the other side with an unexposed light-sensitive photographic emulsion, the temperature and time conditions required in setting the adhesive being such as to result in a material reduction in sensitivity of the photographic emulsion, and the sensitivity of said emulsion being sufficiently greater than that necessary for the service intended to compensate for said reduction in sensitivity.

30 10. An adhesive photosensitive material according to claim 9, characterized in that the heat-setting adhesive, once set, has light-transmitting qualities at least as good as those of the sheet material.

35 11. An adhesive photosensitive material comprising a sheet material coated on one side with an unexposed supersensitive photographic emulsion and coated on the other side with a water-proof heat-setting adhesive, the supersensitivity of said photographic emulsion being related to and determined by the temperature and time conditions required to set said adhesive.

40 12. An adhesive photosensitive material according to claim 11, characterized in that the heat-setting adhesive, once set, has light-transmitting qualities at least as good as those of the sheet material.

13. An adhesive photosensitive material comprising a sheet material coated on one side with an unexposed supersensitive photographic emulsion and coated on the other side with a waterproof heat-setting adhesive, said emulsion being subject to a material loss of sensitivity under the temperature and time conditions required to set the adhesive and having a supersensitivity great enough to compensate for said loss.

14. An adhesive photosensitive material according to claim 13, characterized in that the heat-setting adhesive, once set, has light-transmitting qualities at least as good as those of the sheet material.
